UNITED STATES PATENT OFFICE.

TILGHMAN B. SNYDER, OF SNYDER'S, PENNSYLVANIA.

RADIATOR-DRUM.

SPECIFICATION forming part of Letters Patent No. 533,887, dated May 7, 1895.

Application filed December 22, 1894. Serial No. 532,679. (No model.)

To all whom it may concern:

Be it known that I, TILGHMAN B. SNYDER, of Snyder's, in the county of Schuylkill and State of Pennsylvania, have invented certain new and useful Improvements in Radiator-Drums; and I do hereby declare that the following is a full, clear, and exact description thereof, reference being had to the accompanying drawings, and to the letters and figures 5 of reference marked thereon, which form part of this specification.

This invention is an improved smoke-drum or hot air radiator and its object is to enable the smoke or hot air to be caused to circulate 15 through the radiator in various ways so as to obtain the greatest amount of heat therefrom and retard or expedite the passage of the hot air therethrough as may be desired.

It consists therefore in the novel construction and combination of parts hereinafter described and claimed.

Referring to the drawings, Figure 1 is a perspective view of the upper and lower drums and intermediate pipe-section of the radiator, 25 the latter being separated from the drums, so as to expose the interior construction of the latter. Fig. 2 is a longitudinal vertical section through the bottom drum, showing the main damper in two positions by aid of dotted lines. Fig. 3 is a side view of the top drum with side wall broken away to show the interior thereof.

As represented in the drawings, my radiator comprises an upper drum or head, a lower 35 drum and a series of intermediate pipes connecting said drums.

The shape of the drums is not essential; and may be varied, and the external ornamentation may be as ornate as desired.

The lower drum (A) is hollow and has a central smoke inlet opening (a) in its bottom, its 40 sides being tight. In it is a central transverse main damper (B) on one side of which is a partition (C) and at the other side thereof 45 is a partition (D). These partitions, in connection with the main damper, divide the lower drum into four chambers, 1, 2, 3, 4, respectively, which when the damper is closed, as indicated in Fig. 1, have no direct communication 50 with one another.

The top (A') of drum A has a series of equi-

distant openings (eight being shown) in it, and the bottom (E') of the top drum has a series of similar openings in it, the ends of a series of pipes (P, Q, R, S, T, U, V, W) being 55 connected to the upper and lower drums at such openings.

The upper drum (E) has a central transverse inclined partition (F), on one side of which is a partition G and on the other side 60 thereof a partition H which altogether divide its interior into four chambers 1', 2', 3', 4', as shown.

In the lower drum (when damper B is closed as shown in Fig. 1) pipes P, Q, R, communicate 65 with chamber 1; pipes U, V, with chamber 2; pipes S with chamber 3; and pipes W, T, with chamber 4.

In the upper drum, pipe Q communicates with chamber 1'; pipes P, U, communicate 70 with chamber 2'; pipes R, S, T, with chamber 3' and pipes V, W, with chamber 4'.

The partitions in the drums are so arranged with reference to the pipe openings that the above described communications between 75 pipes and chambers are always maintained in the upper drum, and pipes P, Q, V, S, T, W, always communicate with the same chambers in the lower drum, but by opening damper B in drum A pipes V, R, are respectively caused 80 to communicate with chambers 4 and 3, and shut off from chambers 2 and 1.

In partition D (of drum A) is an opening d' which can be closed by a damper d operated by a rod (d^2) extending through the side of 85 the drum. When said damper is open there is a direct communication between chambers 3 and 4. When damper B is closed the smoke inlet (a) communicates only with chamber 3. When said damper is closed said inlet communicates with both chambers 1 and 2, but not with chamber 3. The end of partition C is beveled so as to fit neatly against the damper when the latter is closed, but when the damper is opened the point of partition C projects into 90 chamber 3, while communication is established under the damper B between chambers 1 and 2. Damper B is slotted (at b) to allow it to rock past the end of partition C.

In partition G of drum E is an opening (g') 100 provided with a damper (g) operated by a rod (g^2) extending through the side of the drum,

and when said damper is open there is a direct communication between chambers 1' and 2'.

The outlet opening *e* in the top of drum *E* 5 communicates with chamber 1' only, in the construction shown.

A damper *r* is placed over the top of pipe *R* in chamber 3' of drum *E*, said damper having a shank (*r'*) which projects through an 10 opening in partition *F* into chamber 1' and its end underlies an inclined rib *g*' on the back of damper *g*. Shank *r'* is pivoted at *r*' and when damper *g* is opened the rib *g*' presses down the end of the shank and lifts damper *r* 15 so that both dampers *g* and *r* will be opened and closed simultaneously. If desired damper *r* may be independently operated.

The construction will be clear from the foregoing description and drawings, and will work 20 out correctly, though owing to the numerous chambers it may appear confusing.

The operation is as follows:

For direct draft.—Open all dampers. Smoke enters both chambers 1 and 2 of lower drum, 25 rises direct through pipes *P*, *Q*, *U*, into chambers 1', 2', of the upper drum, passes from chamber 2' into 1' and out through opening *e*.

For three-way smoke passage.—Shut damper *B*, and open the others. Smoke enters 30 chamber 3 and chamber 4 (through 3) of lower drum; rises through pipes *S*, *T*, *W*, into chambers 3' and 4' of upper drum; descends through pipes *V*, *R*, into chambers 1, and 2, of lower drum; rises through pipes *P*, *Q*, *U*, 35 into chambers 1', 2', of upper drum, and escapes through opening *e*.

For tortuous multiple passage.—Close all dampers. Smoke then enters chamber 3, rises through pipe *S* into chamber 3'; descends 40 through pipe *T* into chamber 4; rises through pipe *W* into chamber 4'; descends through pipe *V* into chamber 2; rises through pipe *U* into chamber 2'; descends through pipe *P* 45 into chamber 1; rises through pipe *Q* into chamber 1', and escapes. In this case the smoke goes up four times and down three times; pipe *R* being cut out of the circuit.

Obviously the number of pipes may be increased, and various changes made in the mechanical construction without departing from 50 the essential invention, which is summarized in the claims.

Having thus described my invention, what I claim as new, and desire to secure by Letters Patent thereon, is—

55

1. The combination of the lower drum having a central transverse damper, and two chambers on each side of said damper; and the upper drum having an outlet opening, two non-communicating chambers on one side 60 of said opening, and two communicating chambers on the other side of said opening, and a damper for closing the communication between said opening; with the series of pipes connecting the said drums, for the purpose 65 and substantially as described.

2. The combination of the lower drum having a central transverse damper over the inlet opening, two chambers at each side of said damper, and a damper adapted to establish 70 communication between two chambers at one side of the main damper; said main damper being adapted to make communication between the other two chambers when it is opened; with an upper chambered drum and 75 connecting pipes, substantially as described.

3. The combination of the upper drum having a central transverse partition, two non-communicating chambers at one side of said partition, and two communicating chambers 80 at the other side thereof, one of which communicates with the escape flue; and a damper for closing communication between the two latter chambers; with a chambered and dampered lower drum, and pipe connections, 85 substantially as described.

4. The combination of the lower drum having four chambers, one of which communicates with the inlet flue or pipe; with the upper drum having four chambers, one of which 90 communicates with the escape flue or pipe; with a series of pipes connecting said drums, the pipes being so arranged that the smoke will be caused to alternately ascend and descend successively through the pipes and 95 pass successively through all the chambers, substantially as described.

In testimony that I claim the foregoing as my own I affix my signature in presence of two witnesses.

TILGHMAN B. SNYDER.
